UNITED STATES PATENT OFFICE.

FRANK L. DODGSON, OF ROCHESTER, NEW YORK, ASSIGNOR TO GENERAL RAILWAY SIGNAL COMPANY, OF GATES, NEW YORK, A CORPORATION OF NEW YORK.

RELAY.

1,391,944.

Specification of Letters Patent. Patented Sept. 27, 1921.

Application filed March 31, 1917. Serial No. 158,821.

To all whom it may concern:

Be it known that I, FRANK L. DODGSON, a citizen of the United States, and resident of the city of Rochester, in the county of 5 Monroe and State of New York, have invented new and useful Improvements in Relays, of which the following is a specification.

This invention relates to relays, and more 10 particularly to relays used in railway signaling systems.

The object of this invention is to improve the construction of relays in general, and more particularly the construction and arrangement of parts which serve to insulate the binding posts of a relay from their supporting panel.

Other objects and advantages of the invention will appear more fully hereinafter in the description of the particular embodiment of the invention selected to explain its principles, mode of operation and features of construction; and the novel features of the invention will be pointed out in the appended claims.

In describing this particular embodiment of the invention in detail reference is made to the accompanying drawings, which form part of this specification, in which like reference characters refer to like parts in the several views, and in which—

Figure 1 is a side elevation of a relay including the improved construction of parts embodying this invention, the lower part of 35 the relay being in vertical section;

Fig. 2 is a front elevation of the relay;

Fig. 3 is a vertical section through one of the binding posts and front contacts of the relay, said section being taken substantially 40 on the line 3—3 in Fig. 1, looking in the direction of the arrows;

Fig. 4 is an enlarged isometric view of one of the insulating blocks used for supporting a binding post;

Fig. 5 is a view similar to Fig. 4 showing a slightly modified construction of the insulating block;

Fig. 6 is an enlarged plan view of the portion of the cover or contact supporting panel of the relay, looking downward upon its upper face; and

Fig. 7 is a view similar to Fig. 6 showing the under face of the supporting panel.

The general construction of the relay

shown in Figs. 1 and 2 forms no part of 55 the present invention and is substantially the same as that shown in my prior Patent, 896,808, August 25th, 1908. The more important parts of the relay comprise a base 1, a metallic cover or contact supporting 60 panel 2, and an electromagnet having two coils 3 and provided with enlarged pole pieces 4. An armature 5 is pivotally mounted on a horizontal axis below the pole pieces 4, and secured to said armature are several 65 contact fingers 6, which are adapted to be moved up and down by the movement of the armature 5 to make electrical contact with front and back contacts, according to the usual and well known operation of 70 relays of this type. Associated with the cover or contact supporting panel 2 are a number of binding posts. Some of these binding posts, as the binding post 7, serve to establish a connection between the outside of 75 the relay case and a flexible connector 8 extending to each respective contact finger 6. Some of the binding posts, as the binding post 9, have laterally extending prongs 10 constituting back contacts for the relay, that 80 is, contacts which coöperate with a contact finger 6 when the relay is deenergized. Some of the binding posts, as the binding post 11, carry contacting pieces which constitute the 85 front contacts of the relay, that is, a contact which is arranged to coöperate with a contact finger 6 and close a circuit when the relay is energized. This invention relates principally to the construction and arrangement of parts whereby these several binding 90 posts are supported in the panel 2 and are insulated from said panel and from each other; and since this construction is substantially the same for each type of binding post, the description of the manner in which one 95 binding post is supported and insulated will suffice for all.

Referring more particularly to Figs. 3, 4, 6 and 7, each of the binding posts 7, 9 and 11 extends through holes 12 in the supporting panel 2, said holes being considerably larger than the binding posts, as shown in Fig. 3. Each binding post is supported in these holes 12 by two insulating blocks, one, 13, bearing against the upper face of the 100 panel 2 and the other, 14, against the lower face. These insulating blocks 13 and 14, when in place, are prevented from sliding 105

movement in every direction relative to the panel 2; and according to the particular embodiment of the invention illustrated, this result is accomplished by forming ridges or 5 ribs 15 on the upper and lower faces of the panel 2 which define in effect shallow recesses 16 shaped the same as the insulating blocks 13 and 14. In this connection, it will be apparent to one skilled in the art 10 that the same immovable connection between the insulating blocks 13 and 14 and the panel 2 may be accomplished in other ways, and if desired, the recesses 16 may be formed as depressions below the general surface of 15 the panel 2, instead of by the ridges or ribs 15. The ridge or rib 15 on two or more sides of each recess 16 is cut away to form notches, as indicated by the reference character 17, in Figs. 6 and 7, these notches 17 20 being disposed substantially in alignment with the holes 12 through the panel 2, for the purpose more fully explained herein-after. The insulating blocks 13 and 14 applied to the upper and lower faces of the 25 panel 2 are for convenience in manufacture constructed the same, although certain features of the structure of each insulating block perform no active function when the block is applied to the upper face, or the 30 lower face, respectively; and it is obvious that these insulating blocks may be constructed differently, if desired.

Referring to Fig. 4, each of the insulated blocks 13 and 14 is provided with a circular 35 hole 18 extending therethrough through which the binding post 11 passes, this hole being a little larger than said binding post, as shown in Fig. 3. In one face of each insulating block 13 and 14 is formed a square 40 or rectangular recess 19, and extending outward from this recess to the outer edge of the block are grooves or channels 20. In the construction shown in Fig. 4 only two of these grooves 20 are shown, while in the 45 modified construction shown in Fig. 5, four of these grooves 20 are illustrated.

Referring particularly to Fig. 3 which illustrates the binding post 11 for a front contact, this binding post 11 is formed with 50 an enlarged squared portion 21 shaped to fit in the recess 19 in the upper insulating block 13. The front contact comprises a piece of carbon 22, or similar material fastened to a contact supporting piece 23 which is integral 55 with a screwthreaded stem 24 adapted to be secured into a tapped longitudinal bore in one end of the binding post 11. This stem 24 also carries a nut 25 by which the binding post 11 is clamped between the insulating 60 blocks 13 and 14. Surrounding the binding post 11 along the portion of the length thereof which passes through the insulating blocks 13 and 14 and the supporting panel 2, is a sleeve or bushing 26 of oiled silk or similar insulating material.

There is preferably provided an appreciable clearance between this insulating bushing 26 and the insulating blocks 13 and 14, and a considerable clearance or air space between this bushing 26 and the supporting 70 panel 2, for the purpose hereinafter explained. Each binding post is provided with the usual nuts 27 by which wires are clamped thereto. When the binding post is in place, as shown in Fig. 3, the upper insulating 75 block 13 is arranged so that its face, provided with the recess 19 and the grooves 20, is uppermost, in such position that the enlarged portion 21 of the binding post 11 fits closely in said recess. The lower insulating block 14, however, is reversed, so that its face, provided with the recess 19 and grooves 20, is next to the supporting panel 2. 80

When the construction embodying this invention is applied to a binding post for supporting a back contact, as the binding post 9, the insulating blocks 13 and 14 are disposed in a different way, the lower block 14 having its recessed face outward and the upper block 13 having its recessed face near- 90 est the panel. This difference in arrangement does not modify the action or principle of the invention and is adopted for the simple reason that a binding post, as 9, supporting a back contact is tightened and 95 clamped in place from above, rather than from below. The binding posts, such as the binding post, 7, which are used to establish a connection from the outside of the relay case to the flexible connector or pigtail 8, are supported and insulated exactly 100 the same as the binding post shown in Fig. 3 and hereinbefore described, with the exception that the contact 22, and its support are omitted and replaced by nuts 28 for 105 clamping the pigtail 8 in place.

Heretofore, a common way of supporting and insulating binding posts from metallic supporting panels has been to provide an insulating bushing between the binding post 110 and the panel and two insulating washers on each side of the panel. In using this construction in practice it has been found that the insulating bushing has been sometimes injured and its insulating qualities destroyed 115 by excessive binding and compression. It can be seen that this pressure on the insulating bushing would naturally result in the construction heretofore used, since all sidewise and tilting movement of the binding post, 120 such as would be occasioned by the tightening of the nuts associated therewith, would necessarily have to be borne by this insulating bushing. A further disadvantage of the construction heretofore used is that when excessive differences of potential exist between the binding post and its supporting panel, as for example due to static charges and lightning, not only would the insulating bushing 125 be broken by the breakdown of its in- 130

sulating qualities, but also the parts associated with the binding post would be distorted, disrupted, or to a large extent displaced from their proper positions, sometimes with almost explosive force.

Referring to the construction embodying this invention, it will be noted that each binding post is supported entirely by the insulating blocks 13 and 14, and that these insulating blocks in turn are supported and held against movement by the panel 2. In this way, any pressure placed upon the binding post, as by the act of tightening its nuts, is transmitted to the heavy blocks of insulating material 13 and 14 and from them to the fixed panel 2; and since these blocks may be made of ample strength sufficient to stand such pressure as may ordinarily be applied, it can be seen that a simple and rugged construction is provided. Furthermore, no pressure can be placed upon the relatively thin and weak insulating bushing 26, since ample clearance is provided so that, in the usual position of the binding post and in any position which the binding post may assume under ordinary pressures, said insulating bushing is not cramped or bound in any way.

The space between the insulating bushing 26, the insulating blocks 13 and 14 and the panel 2, affords an air space of considerable volume; and this air space is in communication with the outside air through the grooves 20 in the lower insulating block 14 and the notches 17 in the ribs 15 on the lower face of the panel 2. With such a construction, it is found that the disruptive effect of lightning discharges from a binding post to its supporting panel are very much reduced, the principal damage being the cracking, tearing or breaking of the insulating bushing 26, while the other parts associated with the binding post are not seriously injured, so that in repairing the relay, it is only necessary to put a new bushing 26 in place. The absence of such severe breaking of parts by lightning discharges in the construction embodying this invention is attributed to the fact that the volume of air subject to the heating action of the discharge is many times greater in the improved construction than in the construction heretofore used, and furthermore to the fact that this body of air is in communication with the outside air and may be expelled readily without injuring or breaking the parts surrounding it.

While I have herein illustrated and described one particular construction and arrangement of parts for carrying out my invention, it is apparent that considerable change could be made in the exact form, shape and arrangement of parts by one skilled in the art desiring to apply this invention to particular cases; and I do not wish, therefore, to be restricted to the ex-

act construction and arrangement of parts shown and described.

What I claim as new and desire to secure by Letters Patent of the United States is:

1. In a relay, the combination with a binding post and a metallic supporting panel therefor, flat rectangular blocks of insulating material disposed on opposite sides of said panel and coöperating to constitute the only supporting connection between the binding post and panel, said blocks being relatively heavy and of a size and thickness capable of withstanding the ordinary pressures exerted upon the binding post, said panel and insulating blocks having alined holes therein for receiving the binding post, the hole in said panel being considerably larger in diameter than said post, means for clamping the binding post in place between said insulating blocks, said panel being formed with ridges on both sides engaging all sides of the corresponding blocks so as to hold them against either turning or side-wise movement, said ridges being relatively shallow and extending only part way up along the sides of said blocks.

2. In a relay, the combination with a binding post and a metallic supporting panel therefor, relatively heavy flat blocks of insulating material disposed on opposite faces of the panel, said panel and insulating blocks having alined holes therein for receiving the binding post, the hole in said panel being considerably larger than the binding post, a relatively thin flexible bushing of insulating material surrounding the binding post out of contact with the panel, means for clamping the binding post in place between said insulating blocks, and means for holding said blocks against movement relatively to the panel.

3. In a relay, a metallic supporting panel, flat blocks of insulating material disposed on opposite faces of the panel, a binding post passing through alined holes in the blocks and panel, the hole in said panel being considerably larger in diameter than the binding post, a flexible sleeve of insulating material surrounding the binding post out of contact with the panel, means whereby the binding post and one of the insulating blocks are held against relative turning movement, a nut on the binding post bearing against the other blocks and adapted to clamp the binding post between said blocks, and means on opposite faces of said panel adapted to prevent movement of said blocks in any direction in the plane of said panel.

4. In a relay, a supporting panel, blocks of insulating material disposed on opposite faces of said panel and held against movement in the plane thereof, said panel and insulating blocks having alined holes therein, a binding post passing loosely through said holes, whereby a space is formed be-

tween the binding post and said panel and blocks, one of said blocks being provided with air channels leading from said space to the outside air, and means for clamping the binding post in place between said blocks.

5. In a relay construction, a metallic supporting panel, squared flat blocks of insulating material disposed on opposite faces of the panel, means on the panel coöperating with the squared edges of said blocks for holding them against either turning or side-wise movement, said blocks being relatively heavy and of sufficient strength to withstand the stresses to which the binding post supported thereby is ordinarily subjected, a binding post passing through holes in said blocks and through a hole in the panel larger than said binding post, means for clamping the binding post between said blocks, and a relatively thin flexible insulating sleeve surrounding the binding post where it passes through said panel and out of contact therewith.
- 10 15 20 25

6. In a relay construction, a metallic supporting panel, blocks of insulating material supported by said panel, and a binding post supported by said blocks out of contact with said panel, whereby an inclosed air space is formed between the binding post and the panel, one of said blocks being provided with air passages extending from the inclosed air space to the outside air.

7. In a relay construction, a metallic supporting panel, blocks of insulating material disposed on opposite faces of the panel and held against movement in the plane thereof, a binding post clamped between said blocks with an inclosed air space between it and said panel, one of said blocks being provided with air passages extending from the inclosed air space to the outside air, and a bushing of insulating material interposed in the air space between the binding post and the panel and occupying part of said air space.
- 30 35 40 45

8. In a relay, the combination with a supporting panel and a binding post, of means for insulating said post from said panel, said means providing an air chamber around said post with a vent to the outside air.

- 50 55 60 65
9. In a relay construction, a supporting panel, blocks of insulating material disposed on opposite sides of said panel and held against rotation in the plane thereof, said panel and said blocks having alined holes therein, a binding post passing loosely through said holes, thereby providing an air space between said post and the walls of said holes, and a slot in one face of one of said blocks forming a vent connecting the air space around said post with the outside air.

10. In a relay construction, a supporting

panel having squared recesses formed on opposite sides thereof by projecting flanges, blocks of insulating material disposed on opposite sides of said panel and fitting in said recesses, said blocks and said panel having alined holes therein, a binding post passing loosely through said holes with an air space between it and the walls of said holes, one of said blocks having a groove formed in one of its faces extending outward from the holes therein to the outer edge, one of said flanges having an opening therein alined with said groove, whereby a passageway is formed connecting the air space around said post with the outside air, and means for clamping the binding post in place between said blocks.

11. In a relay construction, a supporting panel, separate and detachable blocks of insulating material disposed on opposite faces of the panel, a binding post clamped between said blocks and extending through a hole in the panel which is larger than said post so as to leave a space between it and said panel, said blocks being relatively heavy and of sufficient strength to support the binding post, means preventing displacement of blocks in the plane of the panel and at the same time permit their detachment upon removal of the binding post, and a relatively thin sleeve of insulating material surrounding the binding post and occupying only part of the space between the post and the panel.

10 15 20 25 30 35 40 45 50 55 60 65 70 75 80 85 90 95 100 105 110 115 120

12. In a relay construction, a metallic supporting panel, blocks of insulating material disposed above and below the panel and having alined holes therein, said panel having integral projections coöperating with the edges of said blocks whereby the blocks are each held against either sidewise or turning movement and are also separately detachable, a binding post extending through the holes in the blocks and through a hole in the panel, said hole in the panel being considerably larger in diameter than said post, said blocks constituting the only supporting connection between the binding post and the panel and being of sufficient strength to withstand the stresses to which the post supported thereby is ordinarily subjected, said binding post having a squared portion near the upper end thereof which fits in a coöperating recess in the upper face of the upper block and a threaded portion above said squared portion to receive nuts for clamping wires thereto, and a contact-carrying stem threaded into the lower end of said post and having a nut thereon coöperating with the lower block to clamp the post in place.

FRANK L. DODGSON.
